US00D996895S

(12) **United States Design Patent** (10) **Patent No.:** **US D996,895 S**
(45) **Date of Patent:** **** Aug. 29, 2023**

(54) **GLASS REFLECTOR**

(71) Applicant: **NETAPPLI CO., LTD.**, Ishikawa (JP)

(72) Inventor: **Makoto Nishida**, Ishikawa (JP)

(73) Assignee: **NETAPPLI CO., LTD.**, Ishikawa (JP)

(**) Term: **15 Years**

(21) Appl. No.: **29/769,062**

(22) Filed: **Feb. 3, 2021**

(30) **Foreign Application Priority Data**

Aug. 27, 2020 (JP) ..... 2020-019913 D

(51) **LOC (14) Cl.** **07-99**

(52) **U.S. Cl.**

USPC **D7/396.2; D7/620**

(58) **Field of Classification Search**

(57) **CLAIM**

The ornamental design for a glass reflector, as shown and described.

DESCRIPTION

FIG. 1 is a front elevation view of a glass reflector showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a first top, right, front perspective view thereof; and,

FIG. 8 is a second top, right, front perspective view thereof. The broken line showing in FIG. 8 is for the purpose of illustrating environmental structure and forms no part of the claimed design.

1 Claim, 8 Drawing Sheets

US D996,895 S
